Specification for Design.

Patented Oct. 13, 1914.

Application filed July 31, 1914. Serial No. 854,409. Term of patent 14 years.

To all whom it may concern:

Be it known that we, CHARLES F. GRAIN-GER and WILLIAM C. BROHM, citizens of the United States, residing at Louisville, in the county of Jefferson and State of Kentucky,
have invented a new, original, and ornamental Design for a Stand, of which the following is a specification, reference being had to the accompanying drawing, forming a part thereof.

The figure is a perspective view of the stand, showing our new design.

We claim:

The ornamental design for a stand, as shown.

CHARLES F. GRAINGER.
